US00D327070S

United States Patent [19]

Watanabe

[11] **Patent Number:** Des. 327,070[45] **Date of Patent:** ** Jun. 16, 1992[54] **HOLDER FOR PORTABLE RADIO
TELEPHONE**

[75] Inventor: Katsuhito Watanabe, Tokyo, Japan

[73] Assignee: Oki Electric Industry Co., Ltd.,
Tokyo, Japan

[**] Term: 14 Years

[21] Appl. No.: 531,531

[22] Filed: May 31, 1990

[30] **Foreign Application Priority Data**

Feb. 22, 1990 [JP] Japan 2-5370

[52] U.S. Cl. D14/251; D14/138

[58] Field of Search D14/137, 138; D13/108,
D13/107; 379/61[56] **References Cited****U.S. PATENT DOCUMENTS**
